UNITED STATES PATENT OFFICE.

THOMAS F. WALSH, OF ALEXANDRIA, NEBRASKA.

STOCK-CAR PARTITION.

Application filed June 13, 1921. Serial No. 477,219.

To all whom it may concern:

Be it known that I, THOMAS F. WALSH, a citizen of the United States, residing at Alexandria, in the county of Thayer and State of Nebraska, have invented certain new and useful Improvements in Stock-Car Partitions, of which the following is a specification.

In handling mixed shipments of live stock, 10 the railroad companies and the shippers are compelled to separate the various classes. This is also true if one or more fractious animals are included in a shipment of live stock. This separation is usually accomplished by first leading one group of animals, driving them into one end of the car, and then segregating them by means of rails and beams extending across the car. These rails and beams are secured to the frame of 20 the car by means of spikes. The process is then repeated with the next group of animals, and so on until the car is loaded.

This method entails a large amount of labor in fitting and nailing the rails and beams, and the time lost is wasteful to the railroad company in idle stock cars and to the shipper in the undue excitement and resultant loss of weight in the cattle. During the journey the cattle often get their feet 30 through between the rails, thus requiring frequent attention on the part of the attendant to prevent broken legs. After unloading, the spikes are often left protruding from the frame of the car, and the railroad company is liable for damages resulting 40 from injuries to subsequent shipments of stock. The frequent repetition of this process of spiking temporary partitions splits the car beams and very materially lessens the life of the car.

To obviate these difficulties, my invention has for its object a portable partition which is strong enough to withstand the rough usage which it must get, but light enough to be carried and put into place by one man. With this and other objects in view, my invention is fully described and shown in the specification and accompanying drawings, in which

50 Fig. 1 illustrates the invention in use to divide off a section of the car, the partition extending from side to side of the car, and

45 Fig. 2 illustrates the invention as it may be used to confine one or at most a few head 55 of stock at the end or side of the car.

The partition consists of two similar sec-

tions having a combined length of approximately the width of a stock car. These sections are formed of upper channel iron beams 1 and 2 which are curved at both 60 extremities, lower channel iron beams 3 and 4 which are similarly curved at their extremities, and upright channel iron beams connecting the upper and lower beams near their extremities. A channel iron beam located approximately midway between the upper and lower beams, and parallel to them, connects the upright beams of each section and gives rigidity to the section. Each section is further braced by an iron or 65 steel rod 5 and 6 near its outer extremity, and on this rod a metal plate 7 is slidably fitted. Two straps 8 each having its ends bent to occupy parallel planes, are provided, and each strap has apertures for the reception 70 of bolts or other fastening means 9 and 10. The outer extremities of the lower beams 3 and 4 are apertured for the reception of bolts 11. Bolts 12 pass through the apertures in the straps 7, and bolt 13 passing through the aperture at the extremity of the beam 2 connects the partition directly to the frame of the car. It should be noted that the aperture in the outer extremity of plate 7 is in alignment with the apertures 75 through which bolts 10 and 11 pass.

Connecting the two sections is a pivot bar 14 which passes through aligned apertures near the inner extremities of the beams 1, 2, 3, and 4. This pivot bar constitutes the 90 pintle of the hinge on which the two sections pivot when folding, unfolding, and adjusting the partition. The lower end 15 of the pivot bar 14 constitutes a shoe and is preferably rounded but may be otherwise provided with a friction reducing surface or element. These means of uniting the sections not only serve to hinge them together, but permit a certain amount of play in the structure when buffeted by the cattle. 95

Numerals 16 and 18 represent beams in the frame structure of the car. Each section of the partition is further provided with an iron or steel fabric 17 with meshes just small enough when in vertical position to 105 prevent the passage of the animal's foot. The edges of the fabric are secured to the upper and lower beams and to the upright beams.

In use, the outer extremity of one of the 110 sections is secured in a predetermined location as follows: Bolt 11 is passed through

the aperture near the extremity of one of the beams 3 or 4 and through the floor of the car, and secured by any appropriate means beneath the car, such as a nut or a cotter pin. Then if the car beam happens to be at the level shown at the right in Fig. 1, beam 2 of the frame is secured directly to the car beam 18 by means of bolt 13, and if additional rigidity is desired, the plate 7 is 10 pushed up flush with the lower surface of the beam 18, and the bolt 13 is passed through apertures in elements 2, 18, and 7 and secured by a nut at its lower end. If however the beam of the car frame is lower 15 or higher than the top of the partition, the brace 8 is used as shown to secure the upper beam 1 or 2 to the car. It will be noted that regardless of the method of fastening, the section is adapted to swing on its fastening 20 means as a hinge.

After one end of the partition has been secured to the side of the car, a passage for the cattle is formed either by swinging the unsecured section on the pintle 14 or by 25 swinging the whole partition on its fastening means as a pivot, or both. The cattle are then driven into the end of the car, the partition is swung into position, and the free end is secured to the opposite wall of 30 the car in the manner before described.

When it is desired to segregate only a few head of stock, the partition may be used in the manner shown in Fig. 2, either at the end or side of the car. The method of securing 35 it to the car and of confining the stock is substantially the same as the one shown in Fig. 1, except that both ends are secured to the same wall. The appliance may be used also in the corner of the car, one section 40 being fastened to the end frame and the other to the side frame of the car.

While my invention is designed primarily for use in connection with stock cars, its utility on farms and in stock yards is obvious. Its light weight combined with great 45 strength, and particularly its great adaptability to practically every kind of a structure, make it invaluable wherever live stock of any kind is handled.

When not in use, the appliance may be 50 folded into a compact bundle. Because of the curved ends of the beams 1, 2, 3, and 4, the two sections may be folded flat. The appliance may then be hung out of the way 55 from a hook, or numbers of them may be

packed into a small space by placing one on top of another, the construction of the hinge being such as to minimize irregularities.

Having fully illustrated and described the preferred form of my invention, I wish it to be understood that I do not limit myself to the specific materials or construction shown and described by way of example, nor in general do I limit myself otherwise than as set forth in the claims, read in connection 65 with the specification.

What I claim as new, and desire to secure by Letters Patent of the United States of America, is:—

1. A partition for stock cars comprising 70 two sections, each section having an upper beam of channel iron and a lower beam of channel iron, the beams being curved at their extremities and on the same side of each section, channel-iron bars connecting the upper 75 and lower beams of each section, a pintle passing through the middle points of the curved extremities at the inner ends of the two sections to hold the sections in hinged relation, and means at the outer ends of the 80 sections for securing the partition to the walls of a stock car.

2. A partition for stock cars, said partition including upper and lower beams provided with aligned apertures at their 85 extremities, a rod connecting the upper and lower beams, a plate slidably mounted on said rod, said plate having an aperture in alignment with the apertures in said upper and lower beams, said apertures being provided for the reception of means for securing the extremities of the partition to the 90 walls of a car.

3. A partition for stock cars, said partition including upper and lower beams provided with aligned apertures at their 95 extremities, a strap having its ends bent into parallel relation, apertures in the parallel ends of the strap, means passing through an aperture in the strap and through an aperture at the extremity of the upper beam for securing said strap to said upper beam, the aperture in the free end of said strap being adapted for the insertion of means for securing said strap to the wall of the car at a 100 higher or lower level than the upper beam of the partition.

In testimony whereof I affix my signature.

THOMAS F. WALSH.
